US0D1020454S

(12) United States Design Patent (10) Patent No.: US D1,020,454 S
(45) Date of Patent: * Apr. 2, 2024

(54) FOOD CONTAINER

(71) Applicant: TIYA Trading & Import Inc., San Francisco, CA (US)

(72) Inventor: Jianquan He, Guangdong (CN)

(73) Assignee: TIYA TRADING & IMPORT INC., San Francisco, CA (US)

() Term: 15 Years

(21) Appl. No.: 29/811,963

(22) Filed: Oct. 18, 2021

(51) LOC (14) Cl. 09-03

(52) U.S. Cl.

USPC D9/429

(58) Field of Classification Search

USPC D9/500, 503, 504, 414, 416, 420, 423, D9/424, 425, 426, 427, 428, 429, 431, D9/432, 434, 435, 436, 443, 452, 453, D9/454, 456, 499, 421, 422, 430; D7/538, 543, 545, 546, 547, 548, 549, D7/550.1, 552.1, 553.2, 553.3, 553.6, D7/553.7, 554.1, 554.2, 554.3, 554.4, D7/647, 387, 392.1, 393, 394, 395, 396.2, D7/900, 602, 500, 601, 629, 709; D3/323

(57) CLAIM

The ornamental design for a food container, as shown and described.

DESCRIPTION

FIG. 1 is a front view of a food container showing my new design;

FIG. 2 a back view thereof;

FIG. 3 is a left side view thereof;

FIG. 4 is a right side view thereof;

FIG. 5 a top view thereof; and,

FIG. 6 is a bottom view thereof.

The broken lines depict portions of the article that form no part of the claimed design.

1 Claim, 4 Drawing Sheets
